UNITED STATES PATENT OFFICE.

MARSHALL L. SHEPHERD, OF MONTGOMERY, ALABAMA, ASSIGNOR TO SHEPHERD AUTOMATIC SWITCH COMPANY, INC., OF MONTGOMERY, ALABAMA, A CORPORATION OF ALABAMA.

RAILWAY-SWITCH MECHANISM.

1,079,889.

Specification of Letters Patent. Patented Nov. 25, 1913.

Application filed June 23, 1913. Serial No. 775,362.

To all whom it may concern:

Be it known that I, MARSHALL L. SHEPHERD, a citizen of the United States, residing at Montgomery, in the county of Montgomery and State of Alabama, have invented new and useful Improvements in Railway-Switch Mechanism, of which the following is a specification.

This invention relates to railway switch mechanism for controlling the passage of rolling stock from a main track to a branch track or siding, and vice versa.

The primary object of the invention is to provide a positive and reliable type of switch mechanism adapted to be automatically operated by the rolling stock and locked and guarded in normal or switch-closing position against surreptitious or accidental adjustment.

20 A further object of the invention is to provide a switch mechanism which is adapted to be automatically operated by the rolling stock from either the main or branch line and to lock the open switch rails against accidental closing and secure their positive control by the rolling stock until the latter has passed from one track to the other.

A still further object of the invention is to provide a switch mechanism which will 30 positively close after actuation and the passage of a train from one track to the other and lock the switch rails in normal or closed position so as to obviate the liability of accidents to following trains, while permitting 35 through trains on the main line to travel over the switch point at high speed, without liability of deranging the switch mechanism.

A still further object of the invention is to provide a switch mechanism which is 40 operable automatically by means under control of the driver or engineer of a car or locomotive and may be also operated in an authorized manner by hand when occasion requires and in conjunction with a suitable 45 switch stand and signal, which is especially adapted to obviate liability of injury to or derangement of any of the working parts of the switch in the travel of the rolling stock over the switch point, and which in 50 various respects affords maximum safe-

guards against accidents to the traveling public.

With these and other objects in view, which will appear as the nature of the invention is better disclosed, the invention consists of the features of construction, combination and arrangement of parts, herein-after fully described and claimed, reference being had to the accompanying drawings, in

60

Figure 1 is a top plan view of the rails and switch mechanism at a switch point, showing the switch rails locked in normal position for travel on the main line. Fig. 2 is a top plan view of parts of the switch mechanism on an enlarged scale, and also showing the switch locked in closed position. Fig. 3 is a view similar to Fig. 2, showing the switch thrown and locked in open position for travel between the main and branch lines. Fig. 4 is a vertical transverse section on line 4-4 of Fig. 2. Fig. 5 is a corresponding vertical transverse section on line 5-5 of Fig. 3. Fig. 6 is a vertical longitudinal section on line 6-6 of Fig. 2. Fig. 7 is a vertical transverse section on line 7-7 of Fig. 6, showing in full and dotted lines the normal and forward positions of the latch tripping device. Fig. 8 is a view similar to Fig. 7, showing the latch tripping device in its forward position and the retracting dog in position to retract the same. Figs. 9 and 10 are sectional plan views of the latch and latch retracting device, showing certain positions thereof. Fig. 10^a is a view showing a mid-position of the latch occurring in a certain phase of operation.

Fig. 15 is a detail section through the latch and allied parts. Fig. 16 is a perspective view of the latch. Fig. 17 is a similar view of the throw bar. Fig. 18 is a top plan view showing a modified form of guard rail. Fig. 19 is a vertical transverse section on line 19-19 of Fig. 18. Fig. 20 is a top plan

100

view showing a modified construction of motion transmitting means operated by the guard rail. Figs. 21, 22 and 23 are sections taken, respectively, on the lines 21—21, 5 22—22 and 23—23 of Fig. 20.

Referring to Figs. 1 to 19, inclusive, of the drawings, 1 and 2 designate the main line rails, 3 and 4 the branch line or siding rails, and 5 and 6 the switch rails connected for 10 movement in unison by the rod 7, said rails 5 and 6 forming a switch point movable laterally to open and close communication between the main and branch lines. The rod 7 comprises a pair of telescopic sections 15 8 and 9, slideable with relation to each other, a spring 10 being inclosed within the section 8 and normally acting to force said sections apart. When the switch is open the spring 10 acts to hold the switch rail 6 pressed 20 against the track rail 2 and adjusts said switch rail to compensate for any abnormal variations in the distance between the track rails due to spreading or other causes, thus 25 insuring said travel of the rolling stock over the switch. In the operation of throwing the switch to open position, the rail 5, which is positively moved, has a greater amplitude of movement than the rail 6, resulting in the spring 10 being compressed or placed 30 under tension to maintain the rail 6 in contact with the rail 2, as well as to insure a positive subsequent closing of the switch and to give an additional safeguard to the travel 35 of the rolling stock over the switch, as hereinafter fully described.

Arranged between the tracks of the main line, in the main line approach to the switch, is a suitable casing 11 bolted or otherwise firmly secured to the ties, and in which is revolubly mounted a drum or roller 12, forming a switch-throwing member. This drum or roller is preferably of the construction set forth in my prior applications No. 651,738, filed Sept. 28, 1911 and Number 45 749,151 filed Feb. 18, 1913, said drum or roller having a spiral groove to receive an operating device upon a traveling car or locomotive, whereby the drum is first turned for a portion of its revolution to unlock and 50 throw the switch and on the final portion of its revolution is returned to normal position, and reset for subsequent operation. I have not considered it necessary to illustrate this device in detail, as its specific construction forms no part of the present invention, and as any suitable device for performing 55 the same functions may be employed.

The switch throwing drum or roller 12 actuates a rock shaft 13 carrying a pair of crank arms 14 and 15. The crank arm 14 is provided with a pin 16 engaging a slotted link 17 connected with a throw bar 18 suitably fastened to the switch rail 5, said crank arm, pin and link forming a lost-motion

connection between the switch throwing device and the switch, whereby provision is made to secure certain successive and independent motions of the operating parts of the switch mechanism. The crank arm 15 is coupled by a chain 19 or other suitable 65 flexible connection, also constituting a lost-motion connection, with a latch controlling rod 20, connected with a latch or tripping device 21, constructed and operating as herein described. 75

Slidably extending through or beneath the rail 3 and fastened to the rail 5 or to the section 8 of the rod 7 is a second throw bar 22, also operating as a switch locking element. The bar 22 is provided with a pair of spaced locking notches or recesses 23 and 24, adapted to be engaged by a pivoted, laterally movable latch 25, to respectively lock the switch in its closed and opened positions. This latch is normally urged into locking 85 position by a spring 26, and is provided with an arm 27 having a V-shaped or triangular lateral projection or cam member 28 adapted for co-operation with the said latch controlling or tripping device 21. The bar 22 90 may be coupled by a suitable connection 29 to a suitable switch stand target or signal 30, whereby the signal will be operated with the switch mechanism to indicate whether the switch is closed or open. The crank 95 arms 14 and 15 are moved in their respective actuating motions in the direction toward the rails 2 and 6, and in the first portion of its actuating motion the arm 14 takes up the lost-motion between the same and the 100 link 17, while during such period the arm 15 takes up the slack in the chain 19 and draws the device 21 forward to trip the latch 25, thus unlocking the switch. On the continued movement of the arm 14, the lost-motion having been taken up, the pin 16 engages and transmits motion through the 105 link 17 to throw the switch from the closed position shown in Figs. 1 and 2 to the open position shown in Fig. 3, for the travel of 110 the vehicle from the main to the branch line. The parts of the switch mechanism in the main line, including crank arms 14 and 15, are then returned to normal position ready 115 for a repetition of the above described operation after the switch is again closed, which movement of the parts back to normal position is permitted without interference with the thrown switch and latch by the lost-motion connections above described. 120

The latch tripping or retracting device 21 depends from and is loosely mounted upon a rock shaft 31 to swing in a direction transversely of the track and said latch tripping device normally occupies the full line position shown in Fig. 7 and lies immediately in rear of the latch cam 28, as shown in Fig. 9. When the connection 19 is drawn

upon by the crank arm 15 to slide the rod 20 forward, the tripping device 21 rides upon the rear inclined face of the cam until it reaches the point of the cam, as illustrated in Fig. 10, thus retracting the latch and momentarily holding it retracted while, at the end of the lost-motion period, the switch is being thrown. When the tooth of the latch comes into alinement with the surface 16 of the bar 22 between the notches 23 and 24, the tripping device 21, whose forward motion is continued, will move past the point of the cam 28, thus releasing the latch so that it will snap into the recess 24 and lock the 15 switch in thrown position. When in this operation, the switch is thrown, it will be noted, as before described, that the switch rail 5, will be moved a sufficient distance from the rail 3 to permit the wheels to 20 travel freely from the rail 1 to the rail 3, while at the same time the spring 10 will be tensioned to hold the rail 6 pressed firmly against the rail 2 to prevent the formation of any intervening gap and to insure the 25 positive and reliable travel of the wheels from the rail 2 to the rail 6 and thence to the rail 4.

The rock shaft 31 forms part of a latch controlling and switch throwing mechanism arranged in the branch line. This latch controlling and switch throwing mechanism comprises a laterally movable bar or rail 32 forming a combined guard rail and switch actuating device, which is adapted 30 to be engaged and moved inwardly from the rail 3 by the flanges of the wheels of the rolling stock traveling along said rail 3. The respective rails 5 and 32 are adapted to be automatically retracted or returned to 35 normal position by spring actuated retracting devices 33 of the structure clearly shown in Fig. 14, the spring or springs controlling the rail 5 being of sufficient strength to automatically return the switch 40 rails to closed position after being thrown and released, while the spring or springs associated with the rail 32 are of sufficient 45 strength to return said rail and the parts positively controlled thereby to normal position after said rail 32 has been moved outwardly and subsequently released. The rail 32 is coupled by suitable connecting rods 34 and cranks 35 with the rock shaft 31, which is journaled in suitable bearings 36 at one side of the switch parallel with the main line rails. Carried by said shaft 50 is a latch controlling member 37 and a switch-throwing arm or member 38. The member 37 is fixed to the shaft in proximity 55 to the latch tripping member 21 and is provided with a contact pin 39 arranged in rear of said latch tripping member, but in advance of the throw arm 28, in the direction 60 of actuating motion of the shaft 31. When

the rail 32 is moved away from the rail 3 by 65 the wheels of rolling stock traveling from the branch line to the main line, and the shaft 31 is rocked on its actuating motion, the pin 39 first comes in contact with the tripping device 21 and shifts the same forwardly from the normal full line position shown in Fig. 7 to the position shown in dotted lines in Fig. 7 and full lines in Fig. 8, thus retracting the latch in the manner previously explained with reference to the 70 operation of the switch throwing device in the main line, after which the arm 38 moves into position to engage a friction roller 40 on a lug 41 depending from the bar 22, so that on the final portion of motion of the 75 shaft 31 the switch will be thrown. The forward motion of the tripping device 21 is yieldingly limited by a buffer spring 42, shown clearly in Fig. 7 and 8.

The latch throwing member 37 carries a 80 pivoted gravity controlled dog or pawl 43 limited in downward motion by a pin 44, said dog having a beveled nose 45 and a shoulder 46 to respectively slide over and engage with a pin 47 on the tripping member 21, whereby to provide a clutch connection between the members 37 and 21 to effect the retraction of said member 21 after having been shifted forwardly to latch re- 85 tracting and releasing positions in the operation of throwing the switch. The heel end of the dog is formed with an inclined or cam surface 48 for engagement with an abutment 49, whereby on the return of the member 37 to normal position the dog will 90 be kicked up and released from engagement with the pin 47 to free the tripping device or member 21 for normal operation. A chain or other flexible connection 50 may lead from the member 21 over a suitable 95 guide pulley 52 to a handle 53 exposed at a suitable point so that the trip member may be manually drawn backward after having been thrown forward under certain 100 contingencies of service as hereinafter ex- 105 plained.

Assuming that the switch is closed and the parts of the switch controlling mechanism are in normal position, and it is desired to automatically throw the switch for 110 the passage of a train from the main line to the branch line, it will be understood that the switch operating member on the locomotive is projected to actuate the drum 12 on its switch throwing motion and re- 115 turn it to normal position. On the first portion of the switch throwing motion of the drum 12 the arms 14 and 15 are moved to respectively take up the lost-motion between the arm 14 and the throw bar 18, and to 120 take up the slack in the connection 20 and throw the tripping device 21 forward to the 125 position indicated in Fig. 10 to retract the

latch 25 and hold it temporarily retracted. On the final portion of the switch throwing motion of the drum 12 and arms 14 and 15, the switch is thrown and the tripping device 21 moved to the dotted line position indicated in Fig. 9, to permit the latch to lock the switch positively in thrown position. On the return motion of the drum 12 to normal position, the arms 14 and 15 are reset, and are permitted to return to their normal positions by reason of the lost-motion connection between the arm 14 and the throw bar 18 and the chain of flexible connection 19 between the arm 15 and rod 20, the switch remaining in locked position and the tripping device 21 in the forwardly thrown position indicated in dotted lines in Fig. 9. When the train enters the branch line, the flanges of the wheels traveling along the rail 3 engage and move the rail 32 away from said rail 3, thus actuating the shaft 31 on its latch controlling and switch throwing motion, which switch throwing motion in this direction of travel of the rolling stock, however, is rendered ineffective because the switch is in thrown position and the contact roller 40 has been shifted its full thrown distance in advance of the arm 38. In such motion of the rail 32 and shaft 31, however, the member 37 is moved forwardly to free the dog 43 and to cause said dog to engage the pin 47 and couple the tripping device 21 to the shaft 31 for subsequent retraction. The parts will remain in this position, with the switch positively locked in thrown position, but with the latch controlling mechanism set to release the latch from the switch throwing mechanism in the branch line, as long as the rail 32 is held pressed outward from the rail 3 by the flanges of the rolling stock. When the last wheel clears the rail 32 and the train has passed the switch and fully entered the branch line, the retracting springs associated with the rail 32 return said rail to normal position, and as a result the rock shaft 31 is turned back to normal position and in so doing retracts the member 37. The member 37 in moving backward carries with it the tripping device 21, which is locked thereto by the dog 43, the tripping device being thus retracted and on its retractive movement passing back to the full line position shown in Fig. 9, thus tripping and retracting the latch and freeing the switch, which is positively and automatically closed by the springs associated with the rail 5. Hence it will be seen that in the travel of rolling stock from the main line to the branch line the switch will first be unlocked, then thrown to open position, locked in thrown position and held locked in thrown position, although the lock controlling mechanism is reset for retracting the lock, until the rolling stock passes fully

into the branch line, when the switch is unlocked and automatically closes and all the parts are returned automatically to normal position.

When a train traveling from the branch line to the main line enters the switch, the rail 32 is pressed away from the rail 3 in the manner previously described, and in this operation the shaft 31 is rocked on its latch controlling and switch throwing motion, both of which are rendered effective to unlock and throw the switch and to relock the switch in thrown position. In such action the shaft 31 transmits forward motion to the member 37, thus causing the pin 39 to engage and move the tripping device 21 forward while the lost-motion between the arm 38 and friction roller 40 is being taken up. The tripping device 21 will, on such forward motion, first engage the point of the cam 28 and retract the latch, at which time the arm 38 will engage the friction wheel 40 and throw the switch, and then the tripping device 21 will move forward to a position in advance of the cam 28, allowing the latch to be projected by its spring to lock the switch in thrown position. This latch controlling and switch throwing action from the rail 32 in the branch line is permitted without interference from the switch throwing device in the main line, owing to the lost-motion connection between the arm 14 and bar 13 and the flexible connection 19 between the arm 15 and rod 20, as will be readily understood. When the member 37 moves forward it also carries with it the dog 43 which automatically engages the pin 47 and couples the tripping device 21 to said member 37 for retraction. When the last wheel of the train traveling on the rail 3 moves out of contact with the rail 32 and releases said rail 32, the rail 32 and rock shaft 31 are automatically retracted by their retracting springs, thus restoring the member 37 and trip device 21 to normal position. As the member 21 moves backwardly it trips and releases the latch from engagement with the recess 24, but, as the wheels of the rolling stock are still in engagement with the switch rail 5, the switch is still held opened. As before described, the switch rail 5 is spaced from the rail 3, when the switch is thrown from either switch throwing device, a distance greater than the width of the flanges of the wheels, and that when the switch is thrown the rail 5 has a greater amplitude of motion than the rail 6, thus maintaining the spring 10 in compressed condition. Consequently when the rail 32 is released for closing movement by the last wheel of the train, the rail 5 is permitted to move back toward the rail 3 to a certain extent under the action of its closing springs and the pressure of the spring 10, but is held by 330

the wheel flanges from entirely closing and is permitted by the wheel flanges to close to an extent less than the distance between the locking recesses 23 and 24. As a result, 5 the spring 10 is still maintained under a compressed condition and, together with the pressure of the wheels, holds the rail 6 against the rail 2, while the throw bar 22 moves back so that the locking projection 10 of the latch engages the face of said bar at a mid-position between the recesses 23 and 24, thus preventing the latch from locking the switch at this stage in either opened or closed position. When the train fully 15 enters the main line and the last wheel traversing the rail 3 clears the switch rail 5, the reaction of the spring 10, coupled with the retractile energy of the closing springs 20 of the rail 5, effects the automatic closing of the switch, whereupon the latch snaps into the recess 23 and locks the switch again in any closed position. By thus locking the switch rails in thrown position during the full period of the travel of a train from the 25 main line to the branch line, and locking the said rails in closed position in the travel of a train from the branch to the main line during the period the wheels of the train hold the guard rail in shifted position, all 30 liability of injury to the switch rails is avoided, such as would be liable to happen where the switch rails are unlocked and held open solely at all times by the pressure of the wheel flanges and are liable to vibrate 35 laterally under the controlling action of wheel flanges varying to a greater or less extent in width.

As at all times the tie-rod connection permits certain independent movements of 40 the rails 5 and 6, and the action of the spring 10, as described, the rails 5 and 6 will always be maintained in proper position for the travel of the rolling stock without liability of injury to or derangement 45 of the switch, while permitting restoration of the switch throwing and lock controlling elements in the branch line to a normal position without closing the switch or accidentally locking it in open or closed position 50 until the train has fully entered the main line, thus securing safety under all conditions of service.

For the purposes of enabling the switch to be thrown by hand whenever required, I 55 provide a weighted manually operable lever 54 loosely mounted on the shaft 31 and provided with a crank arm 55. The arm 55 carries a pin or projection 56 for engagement with the tripping device 21 and is itself 60 adapted for engagement with a pin or projection 57 on the depending lug or projection 41 of the throw bar 22. The relationship of these elements is such as to provide 65 normally separated interengaging means, 70 constituting the equivalent of lost-motion

connections, between the lever or manually operable switch throwing device and tripping device and throw bar. The relationship of the parts is also such that when the lever 54 is raised on its latch releasing and 75 switch throwing motion the pin 56 engages the tripping device 21 and carries it forward to engage the point of the cam 28 and retract the locking device 25 at the moment the arm 55 engages the pin 57, so that on 75 such switch throwing motion of the lever the latch will be retracted on the first portion of the movement of said lever and the switch thrown, the latch released to lock the thrown switch and the trip device moved to 80 the releasing position shown in dotted lines in Fig. 9 on the final portion of the switch throwing movement of the lever.

The switch throwing lever is designed to be employed when required in lieu of the 85 automatic switch throwing device in the main line to open communication between the main and branch lines, the switch being at all times automatically thrown from the branch line. When the switch is thrown by 90 means of the manually operable lever, it will of course be understood that after the switch is thrown the switch will be controlled by the automatic operation of the guard rail in the branch line to control and later effect 95 the closing of the switch as though the switch were thrown by the automatic switch throwing device in the main line or initially through the medium of the guard rail, the guard rail, in other words, subsequently 100 controlling the locking and releasing action. After the lever 54 has been raised to throw the switch, it is released by the operator and drops by gravity back to normal position, 105 in which position it is automatically locked so that it can not be surreptitiously operated or tampered with. For this purpose, I provide the lever with a locking projection 110 58 adapted to engage an automatic locking device 59 of any suitable character, and which may be unlocked by an authorized type of key to free the switch and permit it to be thrown. It will be observed that when the switch throwing lever is in normal or locked position the latch controlling and switch throwing elements thereof are at all times inactive and do not in any way interfere with the automatic control of the switch by the automatic devices in the main and 115 branch lines.

Under some conditions, where the switch is automatically or manually thrown for the passage of a train from the main line to the branch line, or vice versa, and the car or train does not pass fully through the switch, 120 it is desirable to provide means whereby the thrown trip device 21 may be retracted to unlock the switch and permit it to close. For this purpose, I provide the connection 125 50 and operating handle 53 as hereinbefore 130

described, the operation of which will be obvious. It may also be found desirable under some conditions to provide the guard rail 32 with a flange 32^a overlapping the head of the rail 3, in order to secure an increased movement or extent of throw of said guard rail under the action of the wheels of the rolling stock, enabling increased power to be obtained with less friction. It will be understood, of course, that the ends of this flange will be beveled or inclined to readily admit the flanges of wheels between the same and the rail 3.

From the foregoing description, taken in connection with the accompanying drawings, the construction and mode of operation of my improved switch mechanism will be readily understood, and it will be seen that the invention provides a switch mechanism which is adapted to be automatically operated from either the main or branch line for the passage of rolling stock in either direction from one line to the other, and that the switch can not remain open after passage of a train, but will positively close and remain closed until again actuated, so as to prevent accidents to following trains and thus safe guard the traveling public. It will be further seen that the switch throwing devices in the main and branch lines are adapted to operate independently of one another and control a common locking means, whereby the construction is simplified and friction reduced, owing to the minimum number of parts operating at a time. The invention overcomes the well known objections to split and other common types of switches in use, inasmuch as a safe crossing is insured at all times.

It will be understood, of course, that the motion transmitting parts of the switch mechanism will be suitably housed and protected from the elements and from accidental injury, as well as from the damage or operation of the switch by malicious persons or intending train wreckers, the construction being such that the switch can only be thrown under ordinary conditions by the power of passing rolling stock. The advantage of providing means whereby the switch may be manually thrown will be obvious, and it will be understood that, in practice, the automatic switch throwing device in the main line may be omitted, when desired, and the passage of trains between the main and branch lines controlled by the manual switch and automatic switch mechanism in the branch line.

In Figs. 20 to 23, inclusive, I have shown a modified construction in which a longitudinally movable rod or shaft 31^a is substituted for the motion transmitting rock shaft 31 and is actuated from the guard rail 32 by connecting rods 34^a and bell crank levers 35^a. The rod 31^a is connected with one of

the arms of a pivoted bell crank lever 38^a, the other arm 38^b of which is adapted to successively engage the tripping device 21 and a pin or projection 40^a on the throw bar 22 to release the latch and set the tripping device in its forward position and to throw the switch. The said arm 38^b of the bell crank lever 38^a carries the dog 43 and co-operating parts similar to those carried by the throw plate 37 for coaction with the pin or projection 47 on the tripping device 21. The operation with this construction will be apparent from the foregoing description. In this case, it will be seen that the tripping device 21 and manually operable lever 54 are loosely mounted upon an independent shaft 60.

I claim:

1. In a railway switch, a self-closing switch point, a self-projected latch for locking the switch point in closed and opened positions, a latch tripping device, and a plurality of devices for independently controlling said tripping device and throwing the switch.

2. In a railway switch, a self-closing switch point, a self-projected latch for locking the switch point in closed and opened positions, a latch tripping device having forward and backward latch controlling movements, in each of which it is adapted to successively retract the latch to free the switch and to release the latch for subsequent locking operation, a switch throwing device operative to actuate the tripping device on its forward motion and throw the switch, and a second switch throwing device operative to control said tripping device on both of its latch controlling movements.

3. In a railway switch, a self-closing switch point, a self-projected latch for locking the switch point in closed and opened positions, a latch tripping device having forward and backward latch controlling movements, in each of which it is adapted to successively retract the latch to free the switch and to release the latch for subsequent locking action, a switch throwing device operative to move the tripping device on its forward motion and effect the throw of the switch, and means for moving said tripping device on its backward motion to free the switch for an automatic closing action.

4. In a railway switch, a self-closing switch point, a self-projected latch for locking said switch point in closed and opened positions, a latch tripping device having forward and backward latch controlling motions, in each of which it successively retracts the latch to free the switch and releases the latch for a subsequent locking action, means for actuating said tripping device on its forward motion and throwing the switch, and means for actuating said tripping device on each of its motions, said

means being operative to independently throw the switch and to engage and move the tripping device backward for an automatic resetting and switch closing action, in the event of the switch having been primarily thrown by the first-named means.

5. In a railway switch, a self-closing switch point, a self-projected latch for locking the switch point in closed and opened positions, a tripping device movable in one direction to retract the latch to permit the switch to be thrown and release the latch to adapt it to lock the thrown switch, and movable in an opposite direction to retract the latch to permit the thrown switch to be closed to reset the parts for a repetition of the above described operation, means for moving said trip device on its first described motion and throwing the switch, and means for moving said tripping device on its second described motion for a return of the parts to normal position.

6. In a railway switch, a self-closing switch point, a self-projected latch for locking the switch point in closed and opened positions, a latch tripping device movable in one direction to successively retract the latch to free the switch for opening movement and release the latch for locking the switch in opened position, and having a return movement in which it retracts the latch to free the switch for closing movement and assumes a normal inactive position, a switch throwing device for actuating the tripping device on its first-named motion and throwing the switch, and a switch throwing device for independently actuating the tripping device on either of its aforesaid motions.

46 7. In a railway switch, a self-closing switch point, a self-projected latch for locking the switch point in closed and opened positions, a latch tripping device movable in one direction to successively retract the latch to unlock the switch and permit it to be thrown and release the latch to adapt it to lock the switch in closed position, and movable in a reverse direction to successively retract the locking device to free the switch for closing action and release said locking device to adapt it to relock the closed switch, a switch throwing device in the main line for actuating the tripping device on its first-named motion and throwing the switch, and a switch throwing device in the branch line operative when the switch is first thrown by said switch throwing device in the main line to engage the tripping device and move it on its second-named motion, said switch throwing device in the branch line being also adapted to independently move the tripping device on its first-named motion and throw the switch.

8. In a railway switch, a self-closing switch point, a self-projected latch for

locking said switch point in closed and opened positions, a latch tripping device movable in one direction to successively retract the locking device to free the switch for opening movement and release said locking device to relock the switch in opened position, and movable in the reverse direction to successively retract the latch to free the switch for closing movement to release the latch to subsequently lock the switch in closed position, and a throwing device having spaced elements for successively actuating the tripping device and throwing the switch.

9. In a railway switch, a self-closing switch point, a self-projected latch for locking the switch point in closed and opened positions, a latch tripping device movable forwardly to successively retract the latch and unlock the switch for opening movement and release the latch to relock the switch in open position, and adapted on its backward or return movement to successively retract the latch and unlock the switch for closing movement and release the latch for relocking the switch in closed position, an operating member having spaced elements to move the tripping device forwardly and throw the unlocked switch, and means for imparting a return motion to the tripping device for the purpose described.

10. In a railway switch, a self-closing switch point, a self-projected latch for locking the switch point in closed and opened positions, a trip device having a forward movement to successively retract the latch to free the switch for opening movement and release the latch for relocking the switch in thrown position, and a return movement to successively retract the latch to free the switch for an automatic closing movement and to release the latch to relock the switch in closed position, and separate independent switch throwing devices, one operative to move the tripping device forwardly and throw the switch, and the other operative to move the tripping device either forwardly or backwardly and in such forward motion to throw the switch.

11. In a railway switch, a self-closing switch point, a self-projected latch for locking the switch point in closed and opened positions, a latch tripping device having a forward motion to successively retract the latch to free the switch for opening movement and to release the latch to relock the thrown switch, and a backward or return movement to successively retract the latch to free the switch for closing movement and release the latch to relock the switch in closed position, switch throwing devices, each independently operable to move the tripping device on its forward motion and throw the switch, and means controlled by one of said devices for engaging and mov-

- ing the tripping device on its return motion, said means being normally disconnected from the tripping device to permit forward operation thereof by either switch 5 throwing device.
12. In a railway switch, a self-closing switch point, a self-projected latch for locking the switch point in closed and opened positions, a tripping device for controlling 10 the latch for switch opening or closing actions, a switch throwing device for operating the tripping device on its switch throwing action and throwing the switch, and a wheel-controlled, automatically retracted device 15 for actuating the tripping device for switch opening action and throwing the switch independently of said switch throwing device for also automatically actuating the tripping device on its switch closing action. 20
13. In a railway switch, a self-closing switch point, a self-projected latch for locking the switch point in closed and opened positions, a latch tripping device, means for 25 moving said device in one direction for retracting the latch, throwing the switch and relocking it in thrown position, and a wheel-controlled, automatically retracted device for moving the tripping device in such 30 direction and unlocking, throwing and relocking the same in thrown position and for also moving the tripping device in a different direction for retracting the latch and releasing the switch for self-closing action and 35 relocking it in closed position.
14. In a railway switch, an automatically closing switch point, a self-projected latch for locking the switch point in closed and opened positions, a tripping device for primarily retracting the latch and freeing the 40 switch for opening movement and relocking it in thrown position, and secondarily retracting and releasing the latch to free the switch for closing movement and locking it 45 in closed position, a switch throwing device for actuating the tripping member on its primary action and throwing the switch and a secondary switch throwing device operative to control the tripping device on both 50 its primary and secondary actions, said second switch throwing device being adapted to control the thrown switch in the event of the throwing of the switch primarily by the first-named switch throwing device. 55
15. In a railway switch, an automatically closing switch point, a self-projected latch for locking the switch point in closed and opened positions, a tripping device having a primary and operative movement in one 60 direction to retract the latch and free the switch for opening movement and release the latch for locking the switch in thrown position, and a secondary backward or return movement to retract the latch to free 65 the switch for closing movement and free the latch for locking the switch in closed position, a switch throwing device having spaced elements to successively move the tripping device on its primary motion and throw the switch, a second automatically retracted switch throwing device having spaced members to successively move the tripping device on its primary motion and throw the switch, said elements being normally free from its connection with the tripping device, whereby said tripping device may be operated independently on its primary motion by said switch throwing devices, and means controlled by one of said switch throwing devices for coupling it on 70 its primary motion to the tripping device to move said tripping device on its return motion. 75
16. In a railway switch, a self-closing switch point, a self-projected latch for locking the switch point in closed and opened positions, a wheel controlled automatically retracted guard rail, a latch tripping device having a forward motion to successively retract and release the latch and a similar return motion, means actuated by the guard rail on its wheel controlled motion to successively move the tripping device on its forward motion and throw the switch, a second switch throwing device for actuating the 80 tripping member and throwing the switch in like manner, and an automatic coupling connection between the guard rail and tripping device for connecting said tripping device with the guard rail for return motion 85
17. In a railway switch, an automatically closing switch point, a self-projected latch for locking said switch point in closed and opened positions, a normally idle latch tripping device, means for operating said tripping device to retract the latch to free the switch and release the latch for switch relocking action, said means being operative to throw the switch during the latch retracting 90 and releasing periods, and a second train operated automatically retracted switch throwing device operable to control the tripping device and throw the switch in the manner described, when said switch is in 95 closed position, and operable to control the tripping device when the switch is in open position to retract the latch for automatic switch closing and relocking actions. 100
18. In a railway switch, a self-closing switch point, a self-projected latch for locking the switch point in open and closed positions, a latch tripping device having forward and backward movements on each of which it is adapted to successively retract 110 the latch to unlock the switch point and to free the latch for a subsequent locking action, controlling means for successively actu- 115
- 120
- 125

ating the tripping device on its forward motion and throwing the switch between the intervals of the latch retracting and releasing actions of said tripping device, and
5 means for subsequently moving said tripping device on its backward motion to retract the locking device, free the switch for closing action, releasing the latch to lock the closed switch and resetting said tripping

device for a repetition of the operations 10 above described.

In testimony whereof I affix my signature in presence of two witnesses.

MARSHALL L. SHEPHERD.
